UNITED STATES PATENT OFFICE

MICHAEL HAWIE, OF GREENS FARMS, CONNECTICUT

BUCKLE

Application filed October 7, 1930. Serial No. 486,891.

My present invention relates to rustless buckles of the type adapted for attachment to the end of a piece of web without stitching and is designed for use upon suspenders, hose

5 supporters and the like.

The purpose of the invention is to provide a simple and practical buckle structure which may be formed of a single piece of sheet metal and wire frame combined, securely fastened 10 together, not hingedly connected as is very generally practiced in buckles of this class, to proportion and assemble the two parts so that the sheet metal member can be bent intermediate of its length around and secured to 15 aligned end portions of the wire frame and so that one of the upwardly deflected portions of the sheet will be longer than the other and secured to the frame forming a lower bar of the buckle, and so that the upper engaging 20 edge portion of said bar will be deflected forward for engagement with the running portion of a web when threaded therethrough.

Another object of the invention is to provide a buckle that will have a relatively small 25 front or upper exposed bar portion and will be otherwise light in weight and smoothly finished so as not to injure the wearer or garments of the wearer. A further object is to provide a buckle of this type wherein the 30 attached end of the web may be securely fastened by the use of a minimum amount of web.

The buckle further permits but one threading of the web and one swedging operation 35 for the attachment of the web and is equally well adapted for different thicknesses of web. While the engaging edge of the lower bar of the buckle, for the running portion of the web, is preferably provided with teeth, yet for 40 very thin webbing a more compact buckle structure may be used to advantage, having no teeth.

With the above and other objects in view, an embodiment of the invention is shown in 45 the accompanying drawings and this embodiment will be hereinafter more fully described with reference thereto, and the invention will be finally pointed out in the claims.

In the drawings:—

50 Fig. 1 shows a front elevation, in an open

position, of a buckle according to my present invention;

Fig. 2 is an end view of the buckle shown in Fig. 1;

Fig. 3 is a front elevation of a piece of web 55 supporting a hose supporter button-loop and showing a buckle according to the present embodiment of my invention attached thereto.

Fig. 4 is an edge view of the buckle and 60 attached parts shown in Fig. 3;

Fig. 5 is a central vertical sectional view 65 through the buckle in an open position as shown in Figs. 1 and 2, with the end portion of a piece of web positioned therein as in the assembling of the buckle and web; and

Fig. 6 shows a central vertical sectional view 70 through the buckle shown attached to the web, the latter being threaded through the buckle as in Figs. 3 and 4.

Similar reference characters indicate like or corresponding parts throughout the several Figs. of the accompanying drawings.

The buckle of my present invention, as 75 herein disclosed, is formed of wire and sheet metal combined, including a wire frame member and a sheet metal member which is firmly secured to the wire frame and provided with a bendable clamping member that is used in the attachment of the webbing to the buckle by suspender and hose 80 supporter manufacturers.

The method of attaching and threading the web in this buckle is somewhat like that 85 used on other forms of rustless buckles and the buckle is in the same manner well adapted for adjustment and to different thicknesses of web. The buckle comprises an elongated structure having a transverse opening or slot therein to receive the running portion of the web. The wire and sheet metal members are assembled in a manner to form a relatively narrow round upper bar, which is exposed at the front when in use upon a web, while the lower covered portion is formed of the sheet metal member. Another important feature of the buckle is 95 that the sheet metal and wire members are rigidly secured one upon the other and are not hingedly connected together as is com-

mon practice in wire and sheet metal buckle structures.

The buckle herein shown is formed of a sheet metal member 10 and a wire frame member 11, the two being rigidly secured together in a way to form an upper bar 12, a lower bar 13 and a web opening 14. The wire frame member in this instance is of a rectangular form and includes an upper bar 12 and a lower bar formed of the inwardly disposed aligned end portions 15. The side portions 16 of the wire frame each include an intermediate offset 17 whereby the upper portion of the frame, including the web opening 14, is slightly wider than the lower portion in which the end of the web is secured.

The sheet metal member 10 of the buckle is bent centrally around and tightly upon the aligned wire end portions 15 in a way to enclose the same, ferrule-like, and to be securely attached thereto, the longer member or bar 13 being bent upward in spaced relation to the round upper bar, and its ears 18 disposed against the sides 16 of the wire frame. The bar may further be provided with a series of forwardly disposed teeth 19 along its upper edge adjacent the transverse opening 14 for the purpose of engaging the running portion of the web when threaded therethrough. This sheet metal member further includes a shorter web clamping member 20 that is bendable toward the rear surface of the bar between the ends of the frame for the purpose of attaching the end 21 of the web 22 thereto. The upper edge portion of this clamping member may also be provided with a series of teeth that are preferably disposed forward, as shown in Figs. 2 and 5, for the purpose of engaging the end portion of the web when attached thereto. This attachment is performed by inserting and positioning the web in the buckle frame, as indicated in Fig. 5, and then placing the same under a foot press whereby the sheet metal clamping portion 20 is pressed down firmly upon the end of the web just hard enough to form a firm attachment without injury to the web. Ears 24 are formed on the ends of this clamping member 20 to engage the rear side of the ends of the wire frame, in the same manner and for the same purpose as the ears 18 on the fixed bar portion 13 to engage the front side. It will be noted, see Fig. 5, that but a relatively short length of web is required in making this attachment of the web to the buckle thereby incurring a saving of web over the old methods, as heretofore employed.

Having thus described my invention, what I claim and desire to secure by Letters Patent is:

1. A buckle for attachment and threading of a web, comprising a sheet metal member

and an attached wire frame member forming a round upper transverse bar having depending and inwardly disposed aligned end portions, a lower bar portion formed of the sheet metal member bent longitudinally to close tightly around the aligned wire end portions forming a relatively long front bar member and a relatively short rear clamping member, the two said members being disposed upward and secured against opposite faces of the side portions of the wire frame member and both members having forwardly disposed upper gripping edges, there being a transverse opening between the round upper transverse bar and the lower sheet metal bar portion, the rear member forming a web attaching member bendable toward the rear surface of said front bar member and against the wire frame member, the end of a length of webbing adapted to be gripped to the rear side of the buckle between said longer bar member and said attaching member and thereupon looped downwardly over said attaching member and forwardly and upwardly over said longer bar and its gripping edge and from front to rear through said opening beneath said round upper bar.

2. A buckle for attachment and threading of a web, comprising a sheet metal member and an attached wire frame member forming a round upper transverse bar having depending and inwardly disposed aligned end portions, a lower bar portion formed of the sheet metal member bent to close tightly around the aligned wire end portions forming a relatively long front and a relatively short rear member, the longer member of said lower bar portion being disposed upward and secured against one face of the sides of the wire frame and in spaced relation to the round upper bar and having a series of forwardly disposed teeth along its upper transverse edge, there being a transverse opening between the round upper bar and the longer member of said lower bar portion and said rear member being bendable toward the rear surface of said front member and against the opposite face of the sides of the wire frame, the said shorter web attaching member being also provided with a forwardly disposed transverse web gripping edge, the end of a length of webbing adapted to be gripped to the rear side of the buckle between said rear surface and said attaching member and thereupon looped downwardly over said attaching member and forwardly and upwardly over said long front member and its gripping edge and from front to rear through said opening beneath said round bar.

Signed at Bridgeport, in the county of Fairfield and State of Connecticut, this 4th day of October, A. D. 1930.

MICHAEL HAWIE.
